VENTILATING WINDOW

William Marshall, Detroit, Mich., assignor to
 Briggs Manufacturing Company, Detroit, Mich.,
 a corporation of Michigan

Application October 23, 1935, Serial No. 46,298

8 Claims. (Cl. 296—44)

This invention relates particularly to that type of ventilating windows for vehicle bodies or the like, especially door or side windows of automobile bodies, wherein it is desirable to swing or pivotally adjust a window pane or glass panel in a horizontal direction within the window opening to provide a ventilating window through which air may be exhausted from the body.

An object of the invention is to provide a ventilating window of the foregoing type wherein the adjustable glass panel may be raised and lowered and also moved, when raised, into pivotal relation to the stationary frame of the window to permit swinging movement thereof into and out of ventilating position.

A further object of the invention is to provide improved regulator mechanism having a single manual control for raising and lowering the glass panel and for swinging it into and out of ventilating position.

Other objects and advantages of the invention will appear from the following description and appended claims when considered in connection with the accompanying drawings forming a part 25 of this specification.

In said drawings:

Fig. 1 is a fragmentary front elevation, partly broken away, of the inside of a vehicle door embodying the invention with the window in closed position.

Fig. 2 is a fragmentary elevation, partly broken away, of the inside of the vehicle door shown in Fig. 1 with the window in ventilating position.

Fig. 3 is a horizontal section taken substantially along the line 3—3 of Fig. 1.

Fig. 4 is a view similar to Fig. 3 but showing the window glass in ventilating position.

Fig. 5 is a broken vertical section taken substantially along the line 5—5 of Fig. 1.

Fig. 6 is a section, on an enlarged scale, taken substantially along the line 6—6 of Fig. 1.

Fig. 7 is a horizontal section, on an enlarged scale, taken substantially along the line 7—7.

Fig. 8 is a detail horizontal section, on an enlarged scale, taken substantially along the line 8—8 of Fig. 1; and

Fig. 9 is a fragmentary horizontal detail sectional view, on an enlarged scale, taken substantially along the line 9—9 of Fig. 1.

Before explaining in detail the present invention it is to be understood that the invention is not limited in its application to the details of construction and arrangement of parts illustrated in the accompanying drawings, since the invention 55 is capable of other embodiments and of being

practiced or carried out in various ways. Also it is to be understood that the phraseology or terminology employed herein is for the purpose of description and not of limitation, and it is not intended to limit the invention claimed herein beyond the requirements of the prior art.

In the drawings there is illustrated, by way of example, a front door of an automobile having a window glass mounted therein and adapted to be raised and lowered by regulator mechanism and to be swung by the regulator mechanism into ventilating position after the glass has been fully elevated. In the construction shown, the door is hinged at its forward edge and is provided with latch mechanism adjacent its rear edge.

As shown in the drawings, the door comprises a front pillar 20 having an upper rearwardly inclined portion 21, a header 22 and a rear pillar 23. The front and rear pillars, together with the header, define a window opening which is adapted to be closed by a glass panel 24. The edges of the glass 24 are confined by a continuous metal channel frame comprising a front portion 25, a rear portion 26 and upper and lower connecting portions 27 and 28, respectively. The regulator mechanism for operating the glass includes a metal channel member 29. The channel 29 carries a rubber weather strip or seal 10 having an external flange or lip 10a which engages the outer face of the metal frame portion 28 (Fig. 5). The lower portion 28 of the window frame is provided with a bracket or strap 30 secured to the frame, as by welding, which has a longitudinal guide slot to receive a headed upright stud or pin 31 which is secured to one end of a link or crank member 32. To the opposite end of the crank is connected the upper end of an upright rotatable shaft 33, the shaft being secured to the glass retainer or channel 29 by means of a U-shaped bracket member 34 having a cylindrical bearing 34a through which the shaft 33 passes. The bracket member 34 is preferably secured to the retainer or channel 29 by means of spot welding, as shown in Fig. 5. The lower end of the shaft 33 is bent at an angle to the vertical portion 45 thereof and this lower end extends outwardly at 35 to engage in a cam slot formed in a part of the regulator mechanism, as hereinafter described. The mechanism and associated parts extend into the well 36 of the door, this well being formed in any conventional manner by the inner door panel 37, garnish molding 38 and outer panel 39.

The window regulator for raising, lowering and swinging the glass 24 may, in many respects, be

of any suitable construction. In the present instance, by way of example, it comprises a mounting plate 40 secured by means of screws 41 to the inside of the door. The plate 40 carries a pair of intermeshing gears 42 and 43 which are journaled on the plate by means of pivots 44 and 45, respectively. The gears are operated through a pinion 46 on a shaft 47 to which is attached the usual crank handle 48. Secured to the pivot 44 10 is a swinging arm 49 and secured to the pivot 45 is another swinging arm 50, these arms being adapted to be swung in opposite directions upon rotation of the gears.

Secured to the outer end of each of the arms is 15 a stud or button-like device 51 having a shank which is riveted to the end of the arm. Depending from the glass retainer or channel 29 is a pair of spaced bracket members 53 preferably secured to the retainer by spot welding, each provided 20 with a runway or guideway 52 for the heads of the studs 51. Thus, when the arms are moved the studs travelling in the runways raise or lower the window glass dependent upon the direction in which the arms are moved. The forward arm 49 25 is, as shown, enlarged adjacent its connection with the glass panel and is provided with a cam portion which may be substantially triangular in shape. The forward corner or portion thereof is provided with a cam slot 54, the outer part of the 30 cam portion, beyond the cam slot, being offset or bent at 55 to provide a finger 56 which, as best seen in Fig. 5, is offset from the plane of the cam portion of the arm 49.

Located within the window well and secured to 35 the front door pillar 20 is a vertical glass channel or runway 57. Secured to the rear pillar 23 is a glass channel or runway 58. At the forward end of the retainer 29 there is provided a guide member shown as a whole at 59, this guide member having an outer face or plate 60 which is adapted 40 to engage and slide upon the felt lined channel 57. The guide 59 is fastened to the end of the member 29 by means of gusset plates 61 which are preferably spot welded to opposite sides thereof. The opposite end of the retainer member 29 45 is provided with a corresponding guide member 62 secured thereto through the medium of a corresponding gusset plate 63. The face plate 64 of this guide member engages and is adapted to 50 slide upon the felt lined face of the guide channel 58. The members 59 and 62 serve as guides for the glass when it is being lowered into the well or elevated therefrom and prevent longitudinal tilting or shifting of the glass.

55 The molding 38 and outer panel 39 are cut away at 38a and 39a, respectively (see Fig. 6) to permit the passage of the mechanism for swinging the glass into ventilating and non-ventilating positions.

60 Referring particularly to Figs. 3, 4, 5, and 7, suitable weather stripping is provided for sealing the window opening around the upper edge or portion 21 of the glass frame and at the front and rear portions 25 and 26, respectively, thereof. 65 This weather stripping, as shown, is formed of rubber or other compressible material 65 and may be formed in a single piece or strip. It is provided with an external flexible flange or lip 65a which is adapted to engage the outer face of the glass frame along the upper edge and front and rear edges thereof. The weather or sealing strip 65 is preferably removably secured within the frame surrounding three sides of the window opening and, as shown, has a stiffening member 70 or channel 66 embedded in the base portion there-

of (see Figs. 5 and 7). Thus it will be seen that, except for a cut-away portion providing clearance for the arm 32, the frame for the window glass 24 is entirely surrounded by a rubber sealing strip or strips provided with a surrounding or 5 marginal flange or flanges which engage the marginal frame of the glass to provide a relatively tight joint when the glass is elevated and in non-ventilating position. The weather stripping provides means for effectually sealing the window 10 opening when the glass panel is in closed position.

Referring particularly to Fig. 7, it will be seen that the rear portion 26 of the glass frame is provided with a flanged metal guide strip or member 10 having its base portion secured to the edge of 15 the frame 26 in any suitable manner, as by means of spot welding. The guide 10 has an offset inwardly extending guide flange 71 which is adapted to enter and slide within a U-shaped groove or 20 guide channel 23a formed in the upright metal finish strip or garnish molding secured to the rear pillar 23. The panel portion 200 may be formed integrally with the metal of the pillar and the concealed channel 23a provides a relatively snug fit for the guide 71 while permitting 25 the same to slide therein. Thus the guide 71, which extends the major height of the window opening, and the guide channel 23a interlocking 30 therewith, form a brace along the rear edge of the glass resisting tilting or cocking of the glass when in raised position. This brace together with the connection 30, 31 holds the glass firmly in upright position, while at the same time said brace permits adjustment of the glass horizontally. The guide 71 will travel out of the 35 guideway 23a when the window glass is fully lowered into the well. When the glass is moved into elevated position the flange 71 enters the groove or channel 23a and when the glass is 40 swung into ventilating position as shown in Figs. 2 and 4 the parts 71 and 23a cooperate to provide a hinge or vertical pivot for the rear edge of the glass 24.

The operation of the ventilating window is substantially as follows: When the window is raised 45 the regulator arms 49 and 50 will swing upwardly toward each other, the cam action of the studs 51 in the guideways 52 effecting the elevation of the glass. Upon reaching its fully elevated position, the guide flange 71 of the metal strip 50 or member 10 will be wholly located within the guide channel 23a and thereby provide both a brace and a hinge at the rear edge of the glass panel. In this position the regulator arms 49 and 55 50 are in the positions shown in Fig. 1 with the terminal or free end 35 of the shaft or crank member 33 located within the cam slot 54 and in engagement with the cam portion or inner edge 56a of the offset finger 56. If it is desired to produce a ventilating slot or opening at the 60 forward upright edge of the glass when in elevated position, the operating handle 48 is rotated further in a counter-clockwise direction which causes the cam surface 56a to ride over the free end 35 of the shaft or crank member, thus rotating the shaft and shifting the link 32, causing the pin 31 to travel in the slot of the bracket 30 from its forward position therein, as shown in Figs. 1, 3, and 6, to its rear position, as shown in 65 Fig. 4. During this movement of the parts the glass is shifted laterally or inwardly about its releasable hinge or pivot (71, 23a) to produce the ventilating slot or opening 100. With the 70 glass in this position, as the vehicle moves for- 75

wardly, air is withdrawn by suction from within the body, as indicated by the arrow in Fig. 4.

When it is desired to close the ventilating opening the operating handle 48 is rotated in a clockwise direction, causing the arms 49 and 50 to move outwardly away from one another with their studs travelling in the guideways 52. During this movement, the free end 35 of the crank member 33 is engaged by the cam portion or 10 surface 49a at the rear edge of the cam slot 54, causing the shaft 33 to be rotated and shifting the crank 32 so as to shift or slide the pin or stud 31 along the strip 30 from its rearmost position of Fig. 4 to its forward position of Fig. 3, 15 thus closing the glass panel. Now, if it is desired to lower the glass 24, the clockwise rotation of the operating handle 48 is continued, whereupon the free end 35 of the rotatable shaft 33 rides out of the cam slot 54 and the arms 49 and 50 20 continue their outward and downward movement to lower the glass. During this movement of the glass the guide members 59 and 62 function to prevent tilting of the glass. When the window glass is raised, the free end 33 of the rotatable 25 shaft for shifting the window glass laterally or horizontally enters the cam slot 54 just prior to the completion of the upward closing movement of the glass panel.

I claim:

30 1. In a vehicle door having front and rear pillars defining a window opening, a glass panel slidable vertically in said opening and also movable laterally about a pivot at one upright edge of the glass, said pivot comprising a guide along 35 said edge of the glass and an interlocking channel therefor in a pillar extending the major height of the window opening and terminating at the locality of the window sill.

2. In a vehicle door having front and rear pillars defining a window opening, a glass panel slidable vertically in said opening and also movable laterally about a pivot at one upright edge of the glass, said pivot comprising a guide along 45 said edge of the glass and an interlocking channel therefor in a pillar extending the major height of the window opening and terminating at the locality of the window sill, said guide being arranged to slide into and out of said channel when the glass is fully raised and lowered.

50 3. In a vehicle door having front and rear pillars defining a window opening, a glass panel slidable vertically in said opening and also swingable laterally about a pivot at one upright edge of the glass, said pivot comprising a guide along 55 said edge of the glass and an interlocking channel therefor in a pillar extending the major height of the window opening and terminating at the locality of the window sill, said guide projecting from the edge of the glass transversely 60 to the plane thereof.

4. In a vehicle door having front and rear pillars defining a window opening, a glass panel slidable vertically in said opening and also swingable laterally about a pivot at one upright edge 65 of the glass, said pivot comprising a guide along said edge of the glass and an interlocking channel therefor in a pillar extending the major height of the window opening and terminating at the locality of the window sill, said guide being 70 arranged to slide into and out of said channel when the glass is fully raised and lowered and being offset inwardly from the plane of the glass.

5. In a vehicle door having front and rear pillars defining a window opening, a glass panel adapted to swing laterally in said opening about a pivot at its rear upright edge, said pivot comprising a channel in the rear pillar entirely at 5 the inner side of the glass and a guide along the edge of the glass projecting inwardly and flanged transversely to the plane thereof and fitting into said channel when the glass panel is elevated.

6. In a vehicle body having a window frame 10 provided with a window opening, a framed glass panel for completely closing the window opening adapted to be raised and lowered within said opening and to be shifted laterally when in elevated position to provide a ventilating opening 15 at the forward edge of the glass, said window frame having a fixed guide channel formed in the rear upright portion thereof adjacent the window opening, and a movable guide member carried by the framed glass panel at the rear 20 edge thereof slidable into and out of engagement with said fixed guide channel and providing a pivot for said framed glass panel when the glass is in elevated position whereby to permit horizontal swinging movement of the glass and guide 25 member relative to said guide channel into and out of ventilating position.

7. In a vehicle body having a window frame provided with a window opening, a framed glass 30 panel for completely closing the opening and adapted to be raised and lowered within said opening and to be shifted laterally when in elevated position to provide a ventilating opening at the forward edge of the glass, said window frame having a fixed guide channel formed in 35 the rear upright portion thereof adjacent the window opening, and a movable guide member carried by the framed glass panel at the rear edge thereof, said guide member having a part 40 cooperable with and slidable into and out of engagement with said guide channel and providing a pivot for said framed glass panel when the glass is in elevated position whereby to permit horizontal swinging movement of the glass and guide 45 member relative to said guide channel into and out of ventilating position.

8. In a vehicle body having a window frame provided with a window opening, a framed glass panel for completely closing the opening and adapted to be raised and lowered within said 50 opening and to be shifted laterally when in elevated position to provide a ventilating opening at the forward edge of the glass, said window frame having a fixed guide channel formed in the rear upright portion thereof adjacent the window opening, a movable guide member carried by the framed glass panel at the rear edge thereof slidable into and out of engagement with said 55 guide channel and providing a pivot for said glass panel when the glass is in elevated position whereby to permit horizontal swinging movement of the glass panel and guide member relative to said guide channel into and out of ventilating position, and regulator mechanism for raising 60 and lowering the glass panel and including means for swinging said panel and guide member laterally relative to said fixed guide channel from within said opening into ventilating position when the panel is fully elevated.

70

WILLIAM MARSHALL.
